UNITED STATES PATENT OFFICE

2,605,837

MACHINE FOR NOTCHING SIGNATURES

Alfred Cahen, Cleveland Heights, Ohio

Application August 2, 1948, Serial No. 42,102

1 Claim. (CL 164—49)

1

This invention relates to the art of glued books and consists of an improved form of machine for use in making the same. This application is related to my co-pending application Serial No. 787,322, filed November 21, 1947, to which reference may be had for a fuller understanding of the present invention.

As explained in my co-pending application, supra, the higher grades of books according to the present-day practice have their signatures sewed together while other books have their signatures glued together for the purpose of economy, the present-day gluing method being known in the trade as "perfect binding." The equipment for the sewing operation is quite expensive and that required for the gluing method is also so expensive that only the larger establishments can afford such machines.

Therefore, as in my co-pending application, supra, so here also the general object of the present invention is to make it possible to produce a book with the signature glued together in such manner that the finished book will prove most satisfactory in both appearance and durability and yet can be produced at a reduced cost as compared with both the sewed book and the present-day glued book.

More specifically, the object of my present invention is to devise an improved form of machine for notching the folded edges of the signatures as a preliminary step in the making of a glued book.

A further object is to devise such a machine that is capable of performing the several successive steps comprised in the notching operation in an efficient and dependable manner, including the feeding of the signatures to position within the machine for the notching operation, holding the same in such position, performing the notching operation itself, releasing the signatures and discharging the same therefrom.

As in my co-pending application, supra, so here also it is another object to devise such a machine that can be used in the making of a glued book "two-up"; that is to say, the making of two books together as a unitary whole and then sawing the same in half so as to obtain two separate books with correspondingly increased saving in cost.

Still another object of the present invention, as in the above co-pending application, is to provide a machine for making a glued book in which the end-sheets and inserts, either single-spread or double-spread, may be added wherever desired either between adjacent signatures or

2

within any given signature, without pasting or notching and hence in a convenient and efficient manner.

It is to be understood that the method involved in my present invention may be performed between the usual operations of folding and gathering; and my present machine may be combined with either the folding machine of the bundling press, or may be integrated as part of a combined machine in which may be included also suitable means for performing the folding and bundling operations.

Other objects will appear from the following description and claims when considered together with the accompanying drawing.

Fig. 1 is a side elevation of my present form of machine;

Fig. 2 is a view from the feed-in end of the machine, with parts broken away;

Fig. 3 is an enlarged view of the means for clamping and notching the signatures;

Fig. 4 is another partial detail view of the knife-mounting means; and

Fig. 5 is a view illustrating a notched signature, partially.

It is to be understood that the present operation may be performed immediately after the folding operation and that the signatures of a given book, as they come from the folding machine, will be already arranged in separate groups. Then I proceed to feed the No. 1 signatures into the machine for the notching operation, in the manner to be hereinafter more fully explained, after which I feed the No. 2 signatures into the machine for the same purpose and in the particular manner to be later described, and so on until all of the different groups of signatures have been notched in the manner desired. Then all of the signatures of all of the several groups are ready for the next operation, by which they will be gathered into complete sets including one of each of the several groups Nos. 1, 2, 3 etc., as will be understood from the following. These complete sets of signatures may be bound together in the same manner as set forth in my co-pending application, supra, or in any other suitable manner.

It is to be understood that my present invention relates to only an improved machine for forming the notches in the folded edges of the signatures; and that the subsequent operations in the completion of the book may be understood from the above mentioned co-pending application.

Briefly, my present form of machine comprises clamping means for receiving and effectively holding the signatures one at a time in the notching operation, stop or guide means for determining the exact position to which the signatures are fed and in which they are held between the clamping means, shearing means for forming the notches in the folded edges of the signatures while held between the clamping members, and means for removing the signatures after the notching operation, together with operative connections for repeatedly performing the several operations in a predetermined sequence.

In my present machine, the signatures S are supplied at the proper rate of speed in horizontal flat position along a suitable receiving bed or feed-way so as to enter between the continuously rotating rollers 1, which may be of steel and are positively driven, and the companion rollers 2 operated continuously by mere frictional engagement upon the rollers 1. The rollers 1 are driven through suitable gear connection from the delivery roller means 3, which may be of steel, operated continuously by the sprocket chain drive connection from the intermediate shaft 4 which, in turn, is driven by suitable gears from the shaft 5. The shaft 5 is driven from the main drive shaft 6 of the machine through the chain 7. Rollers 1 and 3 are on shafts 1a and 3a.

The signatures S in succession are fed into position between companion sets of lower fixed clamp means 8 and upper vertically movable clamp means 9, the upper clamp means being automatically opened to receive the signatures, one at a time, and then closed to clamp and hold each signature during the shearing operation. The opening and closing of the upper clamp means 9 is effected through the connecting rods 10 which have cam operating connection with the main drive shaft 6. The clamp means 8 and 9 are provided upon their faces at the delivery side thereof with equally spaced registering vertical grooves 11 and 12, respectively, to accommodate the vertically reciprocable correspondingly formed knives 13 for shearing the folded edges of the signatures S at intervals therealong. The three edges of the lower beveled end of each knife bit 13 are adapted to cut a rectangular notch of desired depth.

The folded edge of each signature S, as it is fed by rollers 1 and 2 to position between the companion clamping means 8 and 9, will engage the upwardly extending rockably mounted guide arms 14 which are adapted to project at their upper ends across the plane of engagement of the signature between the upper and lower clamping means so as to determine the proper position of each signature between the clamping means preparatory to the closing of the clamping means and the shearing operation that immediately follows. Upon engagement of a signature S with the guide means 14, the rear edge of the signature will have passed the rollers 1 and 2, and the rollers 3 will slip idly without disturbing the signature which will then be securely clamped in position. However, when the drop rollers 24, hereinafter referred to, are brought into engagement with the signature upon completion of the shearing operation and opening of the clamping means, there will be effected a positive gripping of the signature frictionally between the rollers 3 and 24 and the signature will be at once expelled from between the clamping means and carried away by the

discharge means at the delivery end of the machine.

The guide arms 14 are mounted upon the bell-crank lever 15 which in turn has operative cam connection with the main drive shaft 6. Each guide arm 14 is adjustable by means of the screw 14a and the locking screw bolt 14b and slot therefor so as to permit different depths of notches according to the thickness of the paper. Each signature in such position will have its folded edge projecting slightly beyond the forward or delivery face of the clamping means, as indicated in Fig. 3, so as to be exposed for the shearing operation of the knives 13 which are operated from above back and forth along a reciprocatory path. These knives are mounted upon the upper transverse bar 16 which is adapted for vertical reciprocatory movement by means of the operative cam connections 17 with the main drive shaft 6, the bar 16 being mounted upon the one end of the laterally extending arm 18 which is rockably mounted about a fixed horizontal axis 19 in the frame of the machine. As soon as a signature has been positioned between the open clamping means 8 and 9, the upper part of the clamping means will be closed into effective engagement upon the signature S while the guide means 14 still occupies active or raised position. Upon complete closure of the clamping means, the guide means 14 will quickly recede so as to be out of the path of the shearing knives 13 which are then brought down at once into operation. There will be sufficient clearance for operation of guides 14.

The shearing knives 13 are mounted so as to extend downwardly from the transverse bar 16 which is adapted for vertical reciprocatory movement through the connecting rods 17 which have operative cam connection with the main drive shaft 6. The knives 13 are so formed and positioned that their paths of movement will be along the registering grooves 11 and 12 provided in the faces of the clamping means 8 and 9, respectively, these parts being fit in a sufficiently snug manner to ensure most efficient clamping and shearing operations.

The bearing of axis 19 may be adjustable along a straight line by means of screw bolt and slot arrangement 19a so as to be able to obtain proper adjustment for the arm 18 and the knives 13.

The arm 18 is of such length and the extent of movement of the shearing knives 13 is so comparatively short that the path described by the knives will be practically a straight line. Furthermore, each individual knife bit 13 has socket engagement near its upper end with an individual set screw or bolt 20 which extends through the companion holder bar 21 and holds the upper end portion of the knife bit 13 against the opposite depending spaced flange 21a of the bar 21 which is mounted upon the transverse bar 16; and each knife bit 13, at its lower end, is resiliently held by a coil spring 22 which extends through the bar 21 and has its rear end engaged against the individually adjustable abutment 23a on the screw bolt 23b in the bar 23 which forms part of the knife assembly, thereby permitting individual setting of the knife bits for proper engagement. This constitutes also an automatic compensating means ensuring effective straight-line movement of the knives within their grooves.

When the edge portion of a signature has been sheared in the manner above explained, the up-

per clamping means 9 will be automatically raised to open position so as to permit ejection of the signature towards the right, as viewed in Fig. 1. For this purpose, I have provided the drop rollers 24 of rubber or other suitable material mounted freely upon the transversely extending shaft 25 which is adapted to be lowered so as to bring rollers 24 into operative engagement with the continuously rotating delivery rollers 3. The ends of shaft 25 have positive connection with upright rods 26 which are connected at their lower ends to the laterally extending rocker arms 27 of the rock shaft 28 which in turn has operative connection through the arms 29 with suitable cam mechanism on the main drive shaft 6. The rollers 24 will be lowered by the coiled springs 30, which are positioned above the ends of the shaft 25, and will be raised out of operative position by the cam mechanism. When immediately following the shearing operation, the drop rollers 24 are lowered by springs 30 into engagement with the signature which extends rearwardly sufficiently for such engagement, there will be positive operative engagement of the same with the signature for further advance movement of the same through the machine so as to be delivered therefrom at the right end thereof, as viewed in Fig. 1. At the delivery end of the machine, endless tapes 31 are driven continuously from shaft 4 for delivery of the notched signatures, it being understood that any suitable means may be provided for this purpose. Immediately upon discharge of notched signatures by the drop rollers 24 and the companion rollers 3, the drop rollers 24 will be automatically raised out of operative position and the next signature will be fed by the rollers 1 and 2 and over the rollers 3 into position between the clamping means 8 and 9, such position being determined by the guide or stop means 14.

It will be explained that the upper and lower clamp means and the shearing means are each formed in laterally arranged pairs. The two lower clamping members 8 are adjustable towards and from each other along the stationary supporting bar 32, these clamp members having the screw bolts 33 which extend through suitable enlarged slots in the bar 32 so that these members may be conveniently adjusted to the desired position and then secured in such position. The two upper clamp members 9 may likewise be adjusted laterally along the transverse bar 34 by means of the screw bolts 35 which are provided upon the members 9 and extend through the enlarged slots in the bar 34. The transverse bar 34 is affixed to the upper ends of the upright plunger rods 36 which extend through the adjustable clamp members 9 and 8 and the transverse bar 32 with suitable clearance to permit such adjustment.

The plunger rods 36 have their lower ends engaged within laterally extending grooves 37 in the upper face of the transverse bar 38 which is adapted for vertical reciprocatory movement by connection with the upper ends of the rods 10. The adjustment of the rods 36 along the grooves 37 permit the lateral adjustment of the clamp members in the manner above described. The upward movement of the bar 37 for opening the clamp means will be against the tension of coil springs 39 which have upward abutment against the under-side of the stationary bar 32 and which are of sufficient strength to return the clamping members downwardly to closed position and to

hold the same effectively in such position during the shearing operation.

The two sets of shearing knives are adjustable laterally upon the transverse bar 16 by means of the screw bolts 40 and 41 which are connected to the holder bars 21 and which are extended through laterally extending slots 40a and 41a in the bar 16. Thus the two sets of knives may be adjusted in accordance with that of the clamping means. The purpose of this arrangement is to change the width of the marginal space between the two parts of the double form of signature which is later to be cut in two, as explained. Or, instead of adjusting the clamping and shearing means, the same result may be accomplished by simply removing or re-inserting any number of the knife bits 13 in the region of this marginal space, as they are individually removable.

The grooves 11 and 12 will be of uniform width and likewise the knives 13 will be all of the same width corresponding to that of the grooves within which they are reciprocated. However, the grooves may be cut back at an angle downwardly and rearwardly and widened at their lower parts so as to facilitate discharge of the sheared portions and to prevent clogging of the grooves.

The knives at the two ends of the knife assembly may be spaced different distances from the ends thereof so that the notches at the two ends of the double signature will be different distances inwardly therefrom. With this provision, I am able to run all of the odd-numbered signatures of a prospective book, that is signatures Nos. 1, 3, 5 etc., through the machine in one position as to right and left ends in the machine, and then run all of the even-numbered signatures, that is Nos. 2, 4, 6 etc., through the machine in reversed end-to-end position. Then, when all of the signatures have been notched and the signatures are made up into book form with the successive signatures 1, 2, 3 etc. in regular arrangement, there will be obtained a staggered arrangement of the notches and a consequent increased strength in the holding effect of the adhesive which is applied to the notched edges of the signatures, as more fully explained in my co-pending application, supra. It is to be understood that the staggered notches may overlap each other, as indicated also in the above co-pending application, when the signatures are assembled and finished in book form. The difference in the spaces at the two ends of the knife assembly will be of proper extent to give the desired degree of overlapping staggered arrangement of the notches of the adjacent signatures.

It is to be understood that the several cams are so designed and arranged with respect to the shaft 6 as to actuate their respective parts of the machine and perform the corresponding operations in the proper sequence in accordance with the modus operandi herein set forth.

With my present machine structure, there may be effected a notching of the signatures in a positive and dependable manner over a long period of time due to the particular form, arrangement and manner of operation of the several parts as herein set forth; there is no interference of the guide or stop means with the operation of the shearing means or with the discharge of the waste sheared portions of paper; the guide means is capable of adjustment for different depths of notches according to the thickness of the paper; the knives and grooves therefor are so designed and the knives are so operated that there is no other danger of clogging of the grooves; the

knives are automatically compensating and may be adjusted or set individually for ensuring most effective and dependable operation; the individual knife bits may be readily sharpened or renewed if ever required; the clamping and notching units may be readily adjusted laterally to vary the marginal space in the middle region of the double signature or a desired number of the knife bits may be removed or re-inserted in this region according to the width of the marginal space desired in any given case; the establishment of the staggered arrangement of the notches in the adjacent signatures of a book is greatly facilitated since no adjustment of the machine is required for this purpose; this machine is capable of comparatively high speed of production and it may be associated with other machines in the making of glued books or may be integrated as a unitary part of a combined machine assembly for performing the several successive operations. Notably, this machine makes it possible to accomplish the general objects as above noted and hence should be the means of placing such a machine within the range of even the smaller establishments so far as the element of cost is concerned. When the glue is applied, it will adhere to all edge portions of each notch as well as to the corners thereof, with the result that there is obtained increased strength. Also, according to my present method, there is approximately fifty per cent less paper cut off than in the case of the "perfect binding" and this also means increased strength as well as a saving in paper and hence in cost. Finally, the employment of my present method may be followed by the regular steps of rounding and back-
ing and thus there may be obtained at a comparatively low cost a finished book having the qualities of a higher priced book. With my present invention, it is possible to make a book of good and dependable quality without having to resort to either of the more expensive methods of sewing and wire-stitching. As is well known, stitching with side wires interferes with and practically prevents opening of the book into flat condition, while stitching with saddle wire is not at all dependable as the leaves come loose. Other advantages resulting from my present invention

will suggest themselves to those who are familiar with the art to which it relates.

It is to be understood that the present form of disclosure is merely for the purpose of illustration and that there might be devised various modifications thereof without departing from the spirit of my invention as herein set forth and claimed.

What I claim is:

In the art of making books, a machine including companion clamping jaws capable of relative movement the one with respect to the other so as to receive and clamp therebetween a book signature with the folded edge of the signature at the outer forward faces of said clamping jaws, means for moving book signatures successively to and progressively through and from position between said jaws, said jaws being provided upon their faces at the outer delivery side thereof with registering grooves across the plane of engagement with a signature, means reciprocatable in said grooves for shearing notches at intervals along the folded back edge of a book signature, said shearing means comprising a unitary assembly of shearing bits, individual resiliently compensating means upon said assembly and in transverse engagement with each of said bits for holding the same in operative position within its groove, and means for effecting in predetermined sequence the operations of said signature-moving means, clamping jaws, and said shearing means.

ALFRED CAHEN.
